UNITED STATES PATENT OFFICE.

FRANK L. SZAFRANSKI, OF DETROIT, MICHIGAN.

SWIMMING DEVICE.

1,304,919.

Specification of Letters Patent. Patented May 27, 1919.

Application filed February 4, 1919. Serial No. 274,926.

To all whom it may concern:

Be it known that I, FRANK L. SZAFRANSKI, a citizen of the United States, residing at Detroit, in the county of Wayne and State 5 of Michigan, have invented certain new and useful Improvements in Swimming Devices; and I do hereby declare the following to be a full, clear, and exact description of the invention, such as will enable others 10 skilled in the art to which it appertains to make and use the same.

This invention relates to swimming appliances and the primary object of the invention is to provide an improved supporting 15 and propelling device for swimmers or bathers.

Another object of the invention is to provide an improved supporting and propelling device for swimmers, which can be actuated 20 by the feet, so that the hands of the swimmer may be free so that he can use the same for firing a gun or the like.

A still further object of the invention is to provide an improved swimming appliance 25 having a pedal arrangement thereon, which is adapted to drive the propeller, so that the device can be operated at a considerable speed through the water.

A still further object of the invention 30 is to provide an improved means for moving the propeller at an angle to the device, so that the device can be readily steered through the water.

A still further object of the invention is 35 to provide an improved swimming appliance, which will keep the swimmer up for a long period of time and one which will allow of considerable speed through the water.

A still further object of the invention is 40 to provide an improved device of the above character, which is durable and efficient in use, one that is simple and easy to manufacture, and one that can be placed upon the market at a reasonable cost.

With these and other objects in view, the invention consists in the novel construction, arrangement and formation of parts, as will be hereinafter more specifically described, claimed and illustrated in 50 the accompanying drawings forming a part thereof, in which:

Figure 1 is a side elevation of the improved swimming appliance,

Fig. 2 is a top plan view of the same, 55 Fig. 3 is a front elevation of the same,

Fig. 4 is a front elevation of the propeller, Fig. 5 is a fragmentary plan view of the device.

Referring to the drawings in detail, 60 wherein similar reference characters designate corresponding parts throughout the several views, the numeral 1 generally indicates the improved swimming appliance which includes a substantially narrow elongated rectangular base plate 2 upon which the swimmer is adapted to recline. The base plate 2 is adapted to be supported in water by a forward pontoon or cylinder 3 and a rear pontoon or airtight cylinder 4. 70 The airtight cylinder 4 is formed relatively larger than the forward cylinder as most of the weight is to be at that part of the device.

The airtight cylinder 3 is provided with a pair of spaced depending eyes 5 in which 75 are secured depending ropes or cables 6 which have their lower ends secured in eyes 7 of bolts 8 which extend through the body 2. The airtight cylinder or pontoon 4 is provided with depending eyes 9 which receive the cables or ropes 10 which have the lower ends thereof secured in eyes 11 carried by bolts 12 which extend through the body 2. The pontoons or airtight cylinders 3 and 4 are spaced a slight distance from 80 the body plate 2, so that the same will be completely submerged when placed in the water. A piece of strap iron 13 is secured to the side of the base plate 2 adjacent the rear end thereof and directly below the rear 85 pontoon 4 and the strap iron has its ends offset as at 14 and bolted as at 15 to the plate. The strap iron and the base plate are provided with aligned apertures, through which is positioned a shaft 16, on which is keyed the relatively large bevel-gear wheel 17.

The bevel-gear wheel 17 is positioned between the base plate 2 and the strap iron 13, which forms a guard for the same. Suitable cranks 18 are secured to the terminals 90 of the shaft. Pedals 19 are formed on the ends of the crank arms so that the bevel-gear 17 may be readily rotated. The rear end of the base plate 2 is provided with an inwardly extending bore 20, in which is fitted a shaft 21, the inner end of which extends into the enlarged portion 22 formed in the base plate. The enlarged portion 22 is provided with a horizontally extending transverse cutout portion 23, in which is fitted a relatively small bevel-gear wheel 24, 100 which is keyed on the shaft 21. The rear 105 portion 22 is provided with a transverse cutout portion 25, in which is fitted a relatively small bevel-gear wheel 26, which is keyed on the shaft 21. The rear 110 portion 22 is provided with a transverse cutout portion 27, in which is fitted a relatively small bevel-gear wheel 28, which is keyed on the shaft 21.

end of the base plate 2 is provided with a pair of spaced extending ears or forks 25, which have pivotally secured thereto by means of a pivot pin 26 a forked member 28, which supports a hollow tubing 29. A relatively short shaft section 30 is rotatably mounted in the tubing 29 and the outer end thereof has secured thereto the relatively large propeller wheel 31 which will hereinafter be more fully described. The shaft section 30 and the shaft 21 are connected together by a suitable ball and socket joint 32 for allowing a movement between the shafts when so desired.

15 The propeller 31 includes the hub 33 having a plurality of pairs of spaced outstanding ears 34 between which is secured the reduced end 35 of the propeller blades 36. The propeller may have any pitch that the swimmer may desire.

20 A suitable spacing sleeve 37 is positioned on the shaft 15 between the crank and the body plate, so as to hold the cranks in the desired position. The lowermost arm of the 25 forked member 28 is provided with outstanding arms 38 which are provided with apertures 39 in which are fitted the terminals of the steering cord 40, which extend through eyes 41 formed in the lower portion 30 of the enlarged portion 22 of the body plate. The guiding rope 40 extends to the forward portion of the device and around a pulley 42 which is carried by the lower end of a bolt 43 rotatably mounted in the 35 forward end of the body plate which is slotted as at 44 and the bolt 43 receives the steering member 45, by means of which the pulley 42 may be turned, so as to move the guiding rope 40 and thus swing the tubular section 29 and the shaft section 30, so as to guide the device through the water. The ends of the steering member 45 are bent inwardly as at 46 to form hand grips, whereby the device may be readily steered.

40 45 In operation of the improved device, the swimmer lies down upon the base plate with

his hands upon the grips 46 and he then places his feet upon the pedals 19 and operates the same in the manner of a bicycle, which turns the propeller 31 and forces the 50 device and the swimmer through the water.

In practice, I have found that the form of my invention illustrated in the accompanying drawings, and referred to in the above description, as the preferred embodiment, is the most efficient and practical; yet realizing the conditions concurrent with the adoption of my device will necessarily vary, I desire to emphasize that various minor changes in details of construction, 60 proportion and arrangement of parts may be resorted to, when required without sacrificing any of the advantages of my invention as set forth.

What I claim as new is:

1. A swimming appliance comprising an elongated body, pontoons carried by the front and rear ends of the body, a pivoted extension formed on the rear end of the body, a propeller carried by said extension, 70 means for operating said propeller, a pulley carried by the forward end of the body, guide ropes extending around said pulley, outwardly extending arms formed on said pivoted section, the terminals of the guide 75 ropes being secured to said arms, and a handle formed on said pulley, as and for the purpose specified.

2. A swimmer's appliance comprising an elongated body, foot-operated propulsion 80 means mounted upon said body, pontoons arranged on the front and rear ends of the body, and flexible means connecting the pontoons and body together, as and for the purpose specified.

In testimony whereof I affix my signature in presence of two witnesses.

FRANK L. SZAFRANSKI.

Witnesses:

JOSEPH ADAM SZCZEPANSKI,
DANIEL GARDYNSKI.
